UNITED STATES PATENT OFFICE.

JOSEPH KAY, OF STOCKPORT, AND JOHN JENNINGS, OF LONDON, ENGLAND, ASSIGNEES
TO PREMIER PRIVATE TELEPHONE COMPANY, LIMITED, OF STOCKPORT, ENGLAND.

TELEPHONE.

Application filed March 22, 1921. Serial No. 454,384.

To all whom it may concern:

Be it known that we, JOSEPH KAY, a subject of the King of England, residing at Edgeley, Stockport, Cheshire, England, and 5 JOHN JENNINGS, a subject of the King of England, residing at Plumstead, London, S. E. 18, England, have invented certain new and useful Improvements in Telephones, of which the following is a specification.

This invention is for improvements in or relating to telephones and has for one of its objects to provide a more convenient arrangement of the mechanism in inter-communication telephone sets.

According to the primary feature of the invention an inter-communication telephone table instrument is provided which is shaped to resemble an ordinary pedestal table instrument having the transmitter fixed to its standard, but which has a base (preferably circular) within the casing of which are housed ringing and speaking bars forming part of the telephone wiring system, together with plunger selector switches to operate therewith, said selector switches projecting through the casing to the outside thereof for finger operation, and being preferably circularly arranged about the standard.

According to another feature of the invention an inter-communication telephone instrument of the type in which selector switches displace a speaking bar to pass therethrough to contact a ringing bar, is characterized in that the speaking bar is mounted to move circularly between guiding studs (for example studs supporting the ringing bar from the casing of the base of the instrument) situated on both sides of it.

According to a further feature of the invention an inter-communication telephone instrument of the type in which selector switches displace a speaking bar to pass therethrough to contact a ringing bar, and are subsequently automatically retained in the depressed position by the speaking bar, is characterized by the provision of a clearing plunger (for example similar in shape to the aforesaid plunger selector switches), independent of the switch lever for the telephone receiver, which plunger projects through the casing of the base similarly to the selector switches and is adapted to be operated to displace the speaking bar to re-

lease any selector switches held depressed by it.

For a more complete understanding of the invention there will now be described, by way of example only and with reference to the accompanying drawings, certain constructions of table instrument according to the invention. It is to be understood, however, that the invention is not limited to the precise constructional details set forth.

In these drawings:—

Figure 1 is a partial elevation of a table instrument. This figure is partly in section, one of the sections being taken on the line 1—1 of Figure 2;

Figure 2 is a plan partly in section on the line 2—2 of Figure 1;

Figure 3 is a detail view of a modification, and

Figure 4 is a diagrammatic view of a portion of the wiring.

Like reference numerals indicate like parts throughout the drawings.

The instrument comprises a hollow circular base 10, and a tubular standard 11 projecting upwardly therefrom, the transmitter 12 being mounted at the top of the standard 11, while projecting transversely from the upper part of the standard is a switch lever 13 the outer part of which is formed as a hook 14 on which to hang the receiver 15. The instrument thus is of the same general appearance as an ordinary table or desk telephone instrument of the candlestick type. Projecting through the upper surface of its base, however, are plunger selector switches 16 which are circularly arranged around the standard 11. These switches 16 may be of any desired number according to the number of instruments included in the inter-communication wiring system. In the drawings six switches 16 are illustrated they being preferably numbered respectively from 1 up to 6 on each instrument in the set. There are intended to be six instruments in the set and on each instrument one of the six switches will be a dummy, namely that numbered "1" on No. 1 instrument and that numbered "2" on No. 2 instrument and so on. This arrangement is not essential but will generally be found desirable in actual practise for convenience in setting up the systems and keeping them in order. The selector switches 16 each com-

prise a rod 17 mounted to slide in an aper- 100
105
110

ture in the upper surface of the base 10, one end of the rod projecting into the interior of the base and the other remaining outside the base. This latter end of the rod 5 is formed with a suitable button whereby the switch may be finger operated, while inside the base the rods carry at their ends conical caps 18 whereof the base which is larger in diameter than the rod 17 is secured 10 to the end of the rod. Between these caps 18 and the casing of the base 10 springs 19 are provided which tend to resist depression of the switches. Conveniently, the springs 19 are housed individually in guides or casings 15 20 for the rods 17 and bear at their lower end against the latter and at their upper end against a pin 21 carried by the rod 17 of the switch to which they are appropriated. The rods 17 are preferably insulated 20 from the material of the base 10 by washers 22, while the casings 20 are carried on an insulating plate 23.

Also within the base 10 of the instrument are a ringing bar 24 and a speaking bar 25. The former is carried from the upper part of the casing of the base by a series of downwardly projecting studs 26 and the speaking bar 25 is situated between the ringing bar and the upper part of the casing 10, 30 being itself also supported by the said studs 26. Both the ringing and the speaking bars are circular or arcuate in shape to correspond with the arrangement of the selector switches and they are so arranged that it is 35 possible to depress any of the switches into contact with either bar, the speaking bar being perforated at 27 to permit the switches to pass through it to reach the ringing bar. During and by reason of passage of a switch 40 through the speaking bar to reach the ringing bar the speaking bar is moved endwise by the switch to bring an appropriate perforation in the speaking bar into alignment with the switch, the conical end 18 of the 45 latter effecting this movement of the speaking bar. This movement of the speaking bar, however, is resisted by a spring 28 with the result that when the conical cap 18 on the end of the switch has passed completely 50 through the speaking bar the latter is moved back into position with its perforation out of alignment with the switch; hence complete return of that switch to its raised position is prevented since the base of the 55 conical cap 18 being flat cannot move the speaking bar to pass through the perforation therein. The switch will thus be held in contact with the speaking bar but out of contact with the ringing bar. The spring 60 28 is attached at one end to the speaking bar and at the other end to a pillar 29 suitably mounted in the base 10. To make efficient contact with the ringing bar 24, the lower end of the switches 16 are preferably 65 provided with contact points 30.

To permit of the aforesaid circular movement of the speaking bar 25 the studs 26 supporting it are arranged on either side of it and are provided with flanges or reduced portions to form shoulders 31 between which the speaking bar is received and by which the bar is prevented from vertical displacement. Conveniently also the speaking bar may be cut away as at 32 for a portion of its side surfaces opposite each stud, such cut away portion being of sufficient length only to permit of the necessary movement to bring the perforations 27 in the speaking bar into and out of alignment with the selector switches but not sufficient to permit of any excessive circular movement of the bar. The studs 26 are preferably insulated from the base 10 by washers 33 and from the ringing bar by bushes 34.

A selector switch when once depressed can only be returned completely to its raised position by circular movement of the speaking bar sufficient to bring the appropriate perforation in the latter into alignment with the conical cap 18 on the switch. This movement of the speaking bar may be effected by the depression of one of the other selector switches or, according to a feature of the present invention, it may be effected by a clearing plunger 35 which may be precisely similar in mechanical construction and operation to the selector switches 16, but it will not, however, like them be connected to the wiring system of the telephone.

The induction coil, the impedance coil and the buzzer are not intended to be mounted inside the base 10 of the instrument as this would make the latter too bulky. They are, however, intended to be housed in a suitable case which may be secured on a wall or on 105 a table or in another situation handy to the telephone instrument.

The wiring of the system may be of well-known character. For example there may be five contacts 36, 37, 38, 39 and 40 inside 110 the standard 11 adjacent the lever 13 on which the receiver is hung. The contacts 36, 37 and 38 are situated on one side of a movable contact 39 on the other side of which is the single contact 40. The movable contact 39 is operated by the lever 13. When the receiver 15 is resting on its hook, the contact 39 bears against the contact 40, and when the receiver is off its hook the contact 39 is coupled to the contacts 36, 37 and 38, and also maintains them in communication with each other. In Figure 4, which shows the wiring for two instruments in a six instrument set, the wiring for instrument No. 1 being shown at the left hand side of this figure and the wiring for instrument No. 2 being shown at the right hand side of this figure, the buzzers are indicated at 41 and 42, the batteries at 43 and 44, the impedance coils at 45 and 46 and 120 125 130

the induction coils at 51 and 52. There are main leads 100, 200, 300, 400, 500 and 600 allocated respectively to instruments Nos. 1-6 and connected to the movable contacts 39 in the standards 11 of those instruments, and also connected to the corresponding selector switch 16 in every other instrument in the set. That is to say the main lead 100 which is allocated to instrument No. 1 is connected to the movable contact 39 in that instrument and to the selector switch numbered "1" in instruments Nos. 2-6. There are also main leads 47, 48, 49 and 50. The lead 47 is connected to the ringing bar 24 of each instrument and to one pole of the battery 44. The lead 48 is connected to the buzzer of each instrument and to the other pole of the battery 44. The lead 49 is connected to the impedance coil of each instrument and to one pole of the battery 43 and the lead 50 is connected to the induction coil of each instrument and to the other lead of the battery 43. The impedance coil for each instrument is also connected to the contact 36 in the standard 11 of its instrument, and the buzzer for each instrument is also connected to the contact 40 in the standard 11 of its instrument. The speaking bar in each instrument is connected to the contact 37 in its instrument and the transmitter 12 in each instrument is connected on the one hand to the induction coil of its instrument and on the other hand to the contact 38 of its instrument.

Thus, if an operator at instrument No. 1 wishes to speak to instrument No. 2 he will depress the switch 16 numbered "2" on his instrument into contact with the ringing bar 24. The circuit will then be 16 (the No. 2 switch on No. 1 instrument), 24, 47, 44, 48, 42, 40, 39, 200, and back to 16. When the operator releases his finger from the switch it moves up automatically into contact with the speaking bar 25. Both operators having lifted their receivers from the hooks a speaking circuit is established as follows:—16 (the No. 2 switch on No. 1 instrument), 25, 37, 38, 12, 51, 50, 43, 49, 46, 36 (No. 2 instrument), 39, 200 and back to 16, with a shunt circuit through 49, 46, 36 (No. 2 instrument), 38, 12, 52, 50 and 43 and back to 49. It will be appreciated that the wiring and operation of this telephone system is well known.

In Figure 3 there is shown a speaking bar similar in all respects to the speaking bar in instrument set No. 2 with the exception that it is perforated for use in a 26 instrument set.

It will be appreciated that according to the present invention there is provided an inter-communication telephone table instrument which is very similar in appearance to an ordinary pedestal or standard telephone table instrument, the difference being, of

course, that projecting through the upper surface of its base are selector switches and the clearing plunger aforesaid. The apparatus according to the invention is therefore very neat in appearance, occupies the minimum of space on the table top and is simple and cheap to manufacture, while being easy of access in case repair or adjustment is needed.

What we claim as our invention and desire to secure by Letter Patent is:—

1. In an intercommunication table or desk telephone of the "candlestick" type, the combination with a cylindrical casing constituting the base of the instrument with one end wall at the bottom thereof, a plurality of pairs of studs arranged in said casing in two parallel arcuate rows mounted on the upper end wall of the casing, an arcuate ringing bar mounted on but insulated from said studs, a spring controlled arcuate speaking bar carried slidable endwise arcuately by sail studs between the ringing bar and the upper wall of the casing and disposed parallel with the ringing bar, said speaking bar having a plurality of perforations arranged in an arcuate row along the same, and a plurality of spring-controlled contact devices in the form of plungers insulated one from another, movable endwise in the upper end wall of the casing and having each at its inner end a shouldered head, each of which heads is adapted to engage said speaking bar in one of said perforations and thereby slide the bar endwise, and is adapted to pass through its allotted perforation and contact with said ringing bar and to be engaged by the speaking bar at the shoulder.

2. In an intercommunication table or desk telephone of the "candlestick" type, the combination with a cylindrical casing constituting the base of the instrument with one end wall at the bottom thereof, a plurality of pairs of studs arranged in said casing in two parallel arcuate rows mounted on the upper end wall of the casing, an arcuate ringing bar mounted on but insulated from said studs, a spring-controlled arcuate speaking bar carried slidable endwise by said studs between the ringing bar and the upper wall of the casing and disposed parallel with the ringing bar, said speaking bar having a plurality of perforations arranged in an arcuate row along the same, and a plurality of contact devices in the form of plungers insulated one from another, each of which contact devices comprises a stem, extending through the upper wall of said casing, a downwardly-directed tapered head constituting a shoulder at the inner end of the stem, a guide for each stem mounted on the underside of the upper wall of the casing, and a coil-spring having one end abutting against the guide and its other end en-

gaging the stem and tending to press the same out of the casing each head being adapted to engage said speaking bar in one of said perforations and thereby slide the bar endwise, and to pass through its allotted perforation and contact with said ringing bar and to be engaged by the speaking bar at the shoulder of the head.

3. In an intercommunication table or desk telephone of the "candlestick" type, the combination with a cylindrical casing constituting the base of the instrument with one end wall at the bottom hereof, a plurality of pairs of studs arranged in said casing 10 in two parallel arcuate rows mounted on the upper end wall of the casing, an arcuate ringing bar mounted on but insulated from said studs, each stud having a horizontal recess between said ringing bar and the upper end wall of the casing, the recess in one stud facing the recess in the opposite stud of the same pair, a spring-controlled ar-

cuate speaking bar carried in the recesses of said studs and disposed parallel with the ringing bar, said speaking bar having means 25 for engaging the studs and thereby limiting its endwise movement in the recesses, and having a plurality of perforations arranged in an arcuate row along the same, and a plurality of spring-controlled contact devices 30 in the form of plungers insulated one from another, movable endwise in the upper end wall of the casing and having each at its inner end a shouldered head, each of which heads is adapted to engage said speaking 35 bar in one of said perforations and thereby slide the bar endwise, and is adapted to pass through its allotted perforation and contact with said ringing bar and to be engaged by the speaking bar at the shoulder of the head. 40

In testimony whereof we have signed our names to this specification.

JOSEPH KAY.
JOHN JENNINGS.
